SPENT BOBBIN RECEIVER AND SUPPORT
THEREFORRichard G. Turner, Worcester, Mass., assignor to
Crompton & Knowles Loom Works, Worcester,
Mass., a corporation of Massachusetts

Application March 26, 1946, Serial No. 657,273

12 Claims. (Cl. 139—255)

1

This invention relates to improvements in weft replenishing looms and it is the general object of the invention to provide an improved form of spent bobbin receiver held in normal position by a support so constructed that the receiver can be slid forwardly therefrom when it is necessary to empty the receiver of the bobbins contained therein.

During weft replenishing operations of a loom the depleted bobbins are pushed downwardly out of the shuttle by the incoming fresh bobbins, and it has been customary in the past to provide some form of receiver or holder for the depleted bobbins. From time to time it is necessary to empty the receiver of the accumulated depleted bobbins and for this reason the receiver should be mounted in such manner that it can be readily removed from its normal position. The receiver should also be prevented from vibrating or swinging during loom operation to insure proper positioning thereof with respect to the downward path of the depleted bobbin. It is an important object of my present invention to provide support means for a bobbin receiver including guideways or open slots to hold parts of the receiver to prevent swinging and vibration thereof but also permit forward movement of the receiver for removal thereof from the loom.

It is another object of my present invention to make the receiver with a bobbin receiving bag supporting frame having means thereon for entering the guideways or open slots. In carrying out this feature of my invention I prefer to use two parallel cross bars on the frame spaced sufficiently to hold the receiver against substantial angular movement relatively to the guideways and also serving as a convenient hand hold by which the receiver may be removed from its support.

In the following description I set forth two different means for supporting the bobbin receiver, one of these comprising an upright secured to the lower part of the loom frame, and the other comprising a suspended hanger above the bobbin receiver. The latter form of support permits adjustment of the bobbin receiver laterally with respect to the path of the outgoing bobbin and also in a direction toward and from the lay.

With these and other objects in view which will appear as the description proceeds, my invention resides in the combination and arrangement of parts hereinafter described and set forth.

In the accompanying drawings, wherein two forms of the invention are shown,

2

Fig. 1 is a side elevation partly in section showing the preferred form of my improved bobbin receiver and its support, the receiver being in normal bobbin receiving position.

5 Fig. 2 is a front elevation looking in the direction of arrow 2, Fig. 1.

Fig. 3 is a plan view looking in the direction of arrow 3, Fig. 2.

10 Fig. 4 is a detail vertical section on line 4—4, Fig. 3.

Fig. 5 is a diagrammatic view showing the manner of removing the bobbin receiver from the support illustrated in Figs. 1 and 2.

15 Fig. 6 is a view similar to Fig. 1 but showing a modified form of bobbin receiver support.

Fig. 7 is a front elevation looking in the direction of arrow 7, Fig. 6.

20 Fig. 8 is an enlarged vertical section on line 8—8, Fig. 7, and

Fig. 9 is a front elevation of the upper part of the modified supporting structure looking in the direction of arrow 9, Fig. 8.

25 Referring particularly to Figs. 1 to 5 which illustrate the preferred form of the invention, I have shown a loom frame 10 and a lay 11 swinging about a rocker shaft 12. The lay is reciprocated backwardly and forwardly by means of connectors one of which is shown at 13. A shuttle box 14 is carried by the lay and receives the 30 shuttle S on alternate beats of the loom. Secured to the lay and depending from the shuttle box is a bobbin guide chute 15 which is inclined downwardly and forwardly. During a weft replenishing operation the bobbin B shown in Fig. 2 is 35 pushed downwardly out of the shuttle S and is guided by the chute 15 along a downwardly and forwardly extending path. This operation occurs when the lay is at its so-called front center position shown in Fig. 1.

In carrying my invention into effect I provide a spent bobbin receiver designated generally at R including a cloth bag 20 and a metallic frame designated generally at 21. The latter may be made of a single piece of metallic tube bent as indicated in Figs. 1 and 2 and having a bottom 22 connected to right and left ascending side members 23 and 24, respectively. Each of these members is bent rearwardly at its upper end to provide a bag supporting arm 25 which as shown more particularly in Fig. 1 is inclined downwardly and rearwardly.

50 The bag 20 may be made of any appropriate flexible cloth material and is suspended from the arms 25 as at 26. Straps 27 secured to the upper part of the bag extend around the side

members 23 and 24 to prevent the bag from sliding rearwardly off the arms 25, and a bottom strap 28 secured to the bag extends forwardly around the side members adjacent to their lower ends to restrict back and forth swaying of the bag 20 relatively to frame 21.

In the preferred form of the invention I provide a stationary support 30 having a foot 31 at the lower end thereof bolted or otherwise permanently secured to the loom frame 10. An 10 upright 32 rising from the foot is provided with a horizontal member or arm 33 supporting right and left guideways 34 and 35, respectively, as shown in Figs. 2 and 3. These guideways are constructed as shown more particularly in Figs. 15 1 and 4 and provide forwardly and upwardly inclined slots 36 which open forwardly. These slots are located between top and bottom side rails 37 and 38, respectively, which are joined at their rear ends to form a stop 39, see Fig. 4.

The receiver frame 21 is provided with front and back parallel horizontal cross bars 40 and 41, respectively, which are permanently secured to and extend between the supporting arms 25. Cross bar 41 is behind and somewhat lower than 25 bar 40 when the side members are vertical as shown in Fig. 1. These cross bars are ordinarily located in the slots 36 as indicated in Figs. 1 and 4 so that the frame 21 is suspended from the member 33 and held against back and forth 30 swinging or vibration during loom operation. The guideways 34 and 35 are sufficiently close to their respective support arms 25 to prevent substantial lateral movement of the receiver R along member 33 in a direction toward and away 35 from the loom frame.

When the bag 20 is sufficiently full of depleted bobbins to require emptying the operator will grasp the two bars 40 and 41 between the guideways 34 and 35 and slide the receiver R forwardly. During this movement the receiver will also rise somewhat due to the inclination of slots 36, but the rear ends of the arms 25 will ordinarily be located far enough below the chute 15 so that they will not engage the latter during this forward and upward movement of the receiver. It will be noted particularly in Fig. 1 that the cross bars 40 and 41 are forward of a vertical line passing through the center of the bag, and because of this relationship the bag and receiver will tend to swing forwardly away from the lay and move the support arms 25 downwardly with respect to the bobbin chute as soon as the cross bars are out of their guideways.

After the bag has been emptied of bobbins the receiver R will be returned to the normal position shown in Fig. 1 by causing the rear cross bar 41 to enter the slots 36, after which the receiver is moved rearwardly until the front cross bar 40 is also located in the slots 36. Because of the relation of the center of gravity of the bag and the cross bars, as already described, the front cross bar 40 may be slightly above the slots 36 when the rear cross bar first enters the slots, but a slight downward motion of the front cross bar by the attendant will enable the bar 40 to enter the slots 36, after which both cross bars are slid rearwardly until the rear bar 41 comes against the stops 39 at the rear of the guideways. The manner of moving the receiver forwardly from its normal position is indicated in Fig. 5, wherein the dotted lines indicate the usual position of the receiver and the full lines indicate a position which the receiver can occupy.

during removal of the receiver and after the cross bars 40 and 41 have been removed from the slots 36.

The modified form of bobbin receiver support shown in Figs. 6 to 9 hangs from a support above the bag 20 and the bag supporting arms 25. As shown in Figs. 6 and 7 the loom is provided with a magazine supporting foot 50 from which extends a stud 51 substantially horizontal and parallel to the lay. This stud in effect is the support for the transfer mechanism not shown by which the depleted bobbins are pushed out of the shuttle S. The bobbin receiver support designated generally at 52 comprises two parts the upper of which serves as a hanger 53 and the lower of which is a guideway supporting member 54. The hanger 53 is provided with a hub 55 held in fixed position on the outer end of stud 51 by set screws 56. As shown more particularly in Fig. 9 the hanger 53 has a web 57 the right and left ends of which are formed with upwardly opening slots 58. The bottom member 54 has upwardly extending arms 59 which register with the slots 58 and are held to the hanger by bolts 60.

The bottom member 54 is provided with a cross bar 61 at the ends of which are located right and left guideways 62 and 63, respectively. These guideways are similar to the guideways described for the preferred form of the invention and provide upwardly and forwardly extending slots 65 which open forwardly and receive the front and back cross bars 40 and 41 respectively of the frame 21. The same receiver R is used for both forms of supports therefor.

The set screws 56 permit the hanger 52 and therefore the bobbin receiver R to be adjusted angularly as viewed in Fig. 6 toward and from the bobbin chute 15, and also laterally as viewed in Fig. 7 toward and from the loom frame 10. This adjustment permits the receiver to be placed correctly with respect to the path traversed by the descending depleted bobbins. It is believed that the manner of removing the receiver R from the modified form of support will be apparent from the description already given in describing the preferred form of the invention. The slots 65 permit the bars 40 and 41 to be slid forwardly out of them and also permit ready return of these cross bars when the emptied receiver R is replaced.

From the foregoing it will be seen that I have provided simple means for supporting a spent bobbin receiver in such manner that it can be readily removed and replaced merely by a sliding movement of the cross bars 40 and 41 with respect to the guideways provided therefor on both the preferred and modified forms of the supports. It will also be seen that the spaced cross bars 40 and 41 cooperate with the guideways to prevent vibration and substantial swinging movement of the receiver R, and at the same time provide a convenient hand hold by which the receiver can be removed from its support.

In the modified form of the invention the supporting structure for the receiver R is made in such manner as to permit adjustments of the latter relatively to the path traversed by the descending depleted bobbin, these adjustments being both angular and longitudinal relatively to the supporting stud 51.

Having thus described my invention it will be seen that changes and modifications may be made therein by those skilled in the art without departing from the spirit and scope of the

invention and I do not wish to be limited to the details herein disclosed, but what I claim is:

1. In a weft replenishing loom, means on the loom defining guideways, a bobbin receiver comprising a framework having forward side members each terminating at the upper end thereof in a rearwardly extending supporting arm, a flexible cloth receiving bag supported by said arms, and a pair of spaced substantially parallel cross bars in said guideways and extending between said arms adjacent to said forward side members and forward of a vertical line passing centrally through said bag, said cross bars cooperating with said guideways to support said receiver.

2. In a weft replenishing loom, means on the loom defining guideways, a bobbin receiver comprising a frame having side members each terminating at the upper end thereof in a rearwardly extending arm, a flexible bobbin receiving bag supported by said frame, and a pair of substantially parallel horizontal cross bars connected to said side members and received by said guideways, one of said cross bars being behind and at a lower level than the other cross bar when said side members are vertical, said cross bars cooperating with said guideways to support said receiver.

3. In spent bobbin receiver means for a weft replenishing loom, stationary supporting structure on the loom formed with horizontally spaced guideways provided with forwardly opening slots, a spent bobbin receiver suspended from said structure, and means on the upper part of said receiver in said slots supporting the receiver on said guideways and preventing angular movement of the lower part of said receiver, said means being slidably forwardly out of said slots to effect removal of said receiver from the supporting structure.

4. In spent bobbin receiving means for a weft replenishing loom having a lay from which spent bobbins are discharged, a structure fixed with respect to the loom and having horizontally spaced guideways provided with slots which open forwardly with respect to the lay, a bobbin receiver suspended from said structure forward of the lay, and means on the upper part of said receiver located in said slots and cooperating with said guideways to prevent substantial angular movement of the lower end of said receiver in a direction toward and from the lay, said means being removable from said slots by forward motion to permit removal of said receiving means from said supporting structure.

5. In spent bobbin receiving means for a weft replenishing loom having a lay from which spent bobbins are discharged, supporting structure fixed with respect to the loom and providing horizontally spaced guideways having slots extending upwardly and forwardly relatively to the lay and open at their forward ends, a spent bobbin receiver in front of the lay, and means on said receiver normally located in said slots and cooperating with said guideways to prevent substantial angular movement of the receiver toward and from the lay, said means being removable from said slots by forward movement to effect removal of the receiver from said support.

6. In spent bobbin receiving means for a weft replenishing loom having a lay from which spent bobbins are discharged, a support fixed with respect to the loom and providing horizontally spaced guideways each open at their forward

ends, a bobbin receiver comprising a frame supporting a flexible bobbin receiving bag, and a pair of horizontal spaced cross bars rigid with said frame normally in said guideways and removable from the latter by forward motion to effect removal of the receiver from the support.

7. In spent bobbin receiving means for a weft replenishing loom having a lay from which spent bobbins are discharged, a support fixed with respect to the loom, a bobbin receiver forward of the lay, and cooperating means including a member on said support and another member of the upper part of said receiver effective to maintain the receiver in normal position on said support, one of said members being slotted downwardly and rearwardly and receiving the other member to prevent angular movement of the receiver in a direction toward and from the lay and constructed to enable said receiver to move forwardly by a sliding motion of one of said members relatively to the other member for removal of the receiver from said support.

8. In spent bobbin receiving means for a weft replenishing loom having a lay from which spent bobbins are discharged, a support fixed with respect to the loom and having forwardly and upwardly inclined horizontally spaced slots open at their forward ends, a bobbin receiver in front of the lay, and means forming part of the receiver located in said slots and tending due to the weight of said receiver to move toward the rear ends of said slots and preventing angular movement of the receiver toward and from the lay with respect to said support, said means being movable out of said slots by forward and upward motion to effect removal of the receiver from the support.

9. In spent bobbin receiving means for a weft replenishing loom having a lay from which spent bobbins are discharged, a horizontally extending support member substantially parallel to the lay, a hanger suspended from said support, means holding said hanger on said support in position adjustable angularly and longitudinally of said support, a bobbin receiver below said hanger and in front of the lay, and cooperating means partly on said hanger and partly on said receiver providing a sliding connection between said hanger and receiver and by which the latter is supported from the hanger and by which the receiver is removable from said hanger by forward motion with respect to the latter.

10. In spent bobbin receiving means for a weft-replenishing loom having a lay from which spent bobbins are discharged, an elongated substantially horizontal support substantially parallel to the lay, a hanger depending from said support, means holding said hanger in angularly and longitudinally adjusted position on said support, a bobbin receiver under the hanger and in front of the lay, and cooperating means partly on said hanger and partly on said receiver constructed and arranged to prevent angular movement of the receiver relatively to the hanger in a direction toward and from the lay when the receiver is in normal position but enabling said receiver to be removed from the hanger by movement forward from the lay.

11. In spent bobbin receiving means for a weft replenishing loom having a lay from which spent bobbins are discharged, an elongated support member substantially parallel to the lay, hanger means suspended from said member and including upper and lower parts, the upper part being connected to and angularly adjustable with re-

spect to said member, means including upwardly opening slots on said upper part for connecting said parts together, guideways on said lower part, and a bobbin receiver having portions movable into and out of said guideways and when in said guideways cooperating therewith to prevent substantial angular movement of the receiver relatively to the hanger in directions toward and from the lay.

12. In a weft replenishing loom having a lay 10 from which spent bobbins are discharged, a horizontal stationary elongated member substantially parallel to the lay, hanger means supported entirely on said member, means to secure said hanger means to said member in any one of a 15 plurality of angularly and horizontally adjusted positions on said member, and a receiver for the discharged bobbins supported entirely by said hanger means and connected to the latter in

such manner as to move as a whole in unison with said hanger means when the latter is moved angularly or longitudinally of said elongated member.
